WILLIAM F. IRRGANG, OF WINDSOR LOCKS, CONNECTICUT, ASSIGNOR TO GEORGE P. CLARK COMPANY, OF WINDSOR LOCKS, CONNECTICUT, A CORPORATION OF CONNECTICUT.

LIFTING-TRUCK.

1,174,580.

Specification of Letters Patent. Patented Mar. 7, 1916.

Application filed March 8, 1915. Serial No. 13,038.

To all whom it may concern:

Be it known that I, WILLIAM F. IRRGANG, a citizen of the United States of America, residing in Windsor Locks, county of Hartford, and State of Connecticut, have invented 5 certain new and useful Improvements in Lifting-Trucks, of which the following is a specification.

This invention relates to improvements 10 in trucks of the lifting type. This class of trucks is widely used at the present time for lifting, lowering, and transferring loads, and its general functions are well understood.

15 Trucks of the lifting type comprise, in general, two relatively movable frames, one of which is mounted on the other and adapted to receive a load and the other to be supported from suitable wheels; lifting 20 devices, which interconnect the relatively movable frames; and mechanism, operable from the steering and drawing handle of the truck, to actuate said devices.

The principal object of the invention is 25 to improve the construction as well as the operating mechanism of the lifting truck to the end that it may be built economically and operated efficiently.

30 The objects of the invention are, more particularly, characterized by the construction and the operative relation of the elements as defined in the annexed claims.

One preferred form of my invention is 35 shown for the purposes of illustration in the accompanying drawings, in which—

Figure 1 is a side elevational view of the truck with the movable frame thereof shown in lowered position; Fig. 2 is a fragmentary cross-sectional view taken on the line 2—2 40 of Fig. 1 and looking in the direction of the arrows; Fig. 3 is a top plan view of a rear corner of the truck with certain portions broken away; Fig. 4 is a sectional plan view taken on the line 4—4 of Fig. 1 and 45 looking in the direction of the arrows; Fig. 5 is a partial sectional elevation of a portion of Fig. 1; Fig. 6 is a side elevational view of the front portion of the truck with the movable frame thereof shown in lifted 50 position; and Fig. 7 is a side elevational view, with parts broken away, of a modification. Fig. 8 is a plan view of the truck,

showing the general arrangement of the parts.

Referring to the drawings in detail and 55 particularly to Figs. 1 to 3, inclusive: 1 represents a frame, preferably of channel section, which is bent into a modified U form. Each of the forward ends of this frame 1 are secured by bolts 8 to a casting 60 2, which arches from and ties the ends of the frame together at the forward end of the truck. Rotatably mounted in the casting 2 is a member 5 having spaced depending webs, between which is mounted a front 65 wheel 6. The rear portion 1' of the U-shaped frame 1 extends transversely of the truck and is bolted to an axle 3, upon which are mounted rear wheels 4. This wheel supported frame structure just described may 70 be conveniently considered as a carriage to bear the load lifting platform and its associated mechanism latch to be described.

The casting 2 is formed on either side 75 thereof with projecting pads 7 (see Fig. 5) against which the frame 1 is bolted. These pads 7 form a pocket on either side of the casting 2 between the frame 1 and the casting to receive links 10. The latter are pivotally connected at 9 to the frame 1 80 and casting 2 as clearly shown in Fig. 2 and are secured by studs 11 to the free ends of a second U-shaped frame 14 which forms 85 a load supporting platform. Near the rear end of the frame 14 is a rod 16 which extends transversely across the frame and is secured thereto as clearly shown in Fig. 3. Loosely mounted on the rod 16 in spaced 90 relation, one at each rear corner of the truck are links 15, which extend to and are rotatably supported upon the rear axle 3. It is to be noted that the links 15 are arranged inside the frame 14 and outside the 95 wheels 4, whereby each link is held against axial movement in either direction by the frame and a wheel without the use of collars and like retaining devices.

Fig. 3 clearly shows the arrangement of the two frames 1 and 14 and one of the link connections therebetween. It will be seen 100 from this figure that the lower frame 1 at each side is inwardly inclined near its rear portion to clear the inside of the wheels 4. The forward ends of the two frames are

substantially in the same vertical plane as will be seen in Fig. 2. It will, therefore, be evident that, when the frame 14 or platform is in its lowered position, as shown in Fig. 1, its engagement with the frame 1 limits the downward movement of the platform at the forward end of the truck. At the rear end the platform 14, when in lowered position, rests on a boss 15' on the link 15.

The links 10, heretofore described, have integral extensions 10' which, when the platform 14 is in lowered position, as in Fig. 1, extend vertically upward. These two spaced extensions 10', one at each front corner of the truck, are connected and tied together by a rod 12 (see Fig. 2). Formed on the rearward side of the extensions 10' are integral buffer plates 13 against which a load placed on the platform 14 may abut.

Pivotedly mounted at 17 between forward extensions of the member 5 is a part 18, which forms a socket for a handle 19. The handle socket 18 has a central opening 25 therein, and, within the latter and pivotedly mounted at 20, is an arm 21. One end of this arm has on either side thereof bosses 23, which are normally engaged by a latch 24. The latter is pivotedly mounted in the handle socket 18 at 25 and is constantly pressed upwardly by a spring 27 (see Fig. 6). The arm 21 has a notch 22, which forms a hook in one end of the arm to engage with the rod 12, when the arm is in the dotted line position shown in Fig. 1. When the handle 19 is in the position shown in Fig. 1, the lower rear surface of the handle socket 18 engages a stop 32 formed on the member 5 as an integral part thereof, 40 whereby the handle is prevented from tipping rearwardly. The abutment of the member 18 against the stop 32 also insures that the handle is properly positioned so that, when the hook arm 21 is released and 45 allowed to drop, the notch 22 will engage the rod 12. It should be noted that, when the arm 21 is released from the latch 24, the latter abuts at its rear end a stop 26, integral with the handle socket 18 (see Fig. 6).

50 When the hook arm 21 is held in the position shown in Fig. 1 by the latch 24, the handle 19 may be used in the usual way to draw and steer the truck. When the handle is not in use for such purposes, it is ordinarily brought into the position shown in Fig. 1, wherein the forward wheel 6 is directed substantially straight ahead, and the handle is prevented from rearward tipping by the stop 32 against which it rests. With the 55 parts in the position shown in Fig. 1, to raise the platform 14, the following procedure is employed: The latch 24 is depressed, preferably and most conveniently with the foot, (a forward extension being provided 60 for this purpose) to release the portion 23

of the arm 21 and to allow the latter to drop by gravity to the position indicated by dotted lines in Fig. 1, wherein the notch 22 engages the rod 12. Thereafter, by pulling downwardly on the handle 19, the links 10 and 15 are rotated on their pivots, and the platform 14 is raised to the position shown in Fig. 6. Foot pieces 28 integrally formed with the member 5 (see Figs. 1 and 4) form a convenient means, whereby the operator 75 may brace himself for the initial pull on the handle 19. When the platform is in the raised position shown in Fig. 6, the rod 12 engages the top surface of the casting 2 to limit further clockwise rotation of the links 80 10. It is to be noted that the center of the stud 11 now lies to the right of the center of the pivot 9 so that the platform 14 and load thereon is held in elevated position by the passing across centers of the arrangement shown of the load supporting points of links 10, whereupon the load tends to turn links 10 to press the cross rod 12 against the top of the casting 2. The end 23 of the arm 21 may now be pushed downwardly by the foot to disengage the arm from the rod 12 and to bring the portion 23 into engagement with the latch 24. The handle 19 is then free for drawing and steering purposes. To again lower the platform 14, the arm 21 is hooked over the rod 12, as shown in Fig. 6, and the handle 19 is pulled upwardly enough to break the lock of the links 10, and, thereafter, the handle is used to ease the downward movement of 100 the frame 14.

Fig. 7 illustrates a modification of the handle-actuated hook, wherein the latch 24 is eliminated. An arm 21' has at one end a hook 22' and at the other end a weighted portion 31. This arm is supported by a pin 20, as heretofore, but the arm 21' is movable on the pin 20 by reason of a closed slot 29. When the pin 20 occupies the position in the slot 29, shown in full lines in Fig. 7, 110 the weight of the portion 31 is sufficient to hold the arm 21' in raised position. When the arm 21' is to be used to actuate the links 10, it is raised preferably by the foot until the pin 20 rests in the slot 30, which is at 115 right angles to the slot 29. With the parts so positioned, the arm 21' may be used as heretofore to actuate the links 10.

In the modification just described the hook arm 21' is disengaged after the platform is raised by pushing downwardly with the foot on weight 31. At this time the handle is lowered so that the hook arm turns clockwise until it moves the slot 29 in line with pin 20, the weight of the hook 120 then causes it to move on pin 20 until it is again in the position relatively to the handle as shown in Fig. 7. By this operation the hook arm may be kept from accidentally falling to strike the front of a high 125 130

load of material as paper in the normal operation of the truck.

It is understood that various modifications may be made in the specific structure heretofore described without departing from the scope of my invention which is defined in the following claims.

What I claim is:

1. A lifting truck comprising a carriage, a platform, means connecting the carriage and platform operable to lift the latter, a pivoted handle on the carriage, an arm pivoted to the handle having a hook to engage and operate said means by movement of the handle, said means and hook arm being constructed and arranged so that the latter has a tendency to fall into engaging position with the former, and foot operable means to hold the arm out of hook engaging position when desired.

2. A lifting truck, comprising, a carriage, a handle therefor, a rearwardly extending hook arm pivoted intermediate its ends at the lower part of the handle, a load lifting mechanism connected to the carriage having means for temporary engagement by said hook and operable by such engagement and the downward sweep of the handle to lift a load and an extension on said hook arm operable by downward foot pressure to disengage said hook arm.

3. A lifting truck, comprising, a carriage, a pivoted handle at the front end thereof, an arm pivoted near the lower end of the handle having a hook portion rearwardly extending from the handle and a controlling portion forwardly extending from the handle, a load lifting mechanism connected to the carriage having means for said hook portion to engage, all constructed and arranged so that a downward sweep of the handle may operate said mechanism and the hook may be disengaged therefrom by movement of said controlling portion by the operator.

4. A lifting truck, comprising, a carriage, a pivoted handle at the front end thereof, load lifting mechanism connected to the carriage, an arm pivoted on the handle near the lower end thereof having a rearwardly extending hook portion for engagement with said mechanism and a forwardly extending controlling portion, the latter having a foot piece at the end thereof, all constructed and arranged so that the handle may operate and control said mechanism by means of the connection with the hook portion and the latter may be disconnected by pressure on said foot piece.

5. A lifting truck, comprising, a carriage, a handle pivoted at the front end thereof, a load lifting mechanism connected to the carriage, an arm having a hook adapted to connect with and operate said mechanism by the movement of said handle on its pivot,

said arm being pivoted intermediate its length near the lower end of the handle so that its rearwardly extending hook portion overbalances its forwardly extending portion, a latch on the handle adapted to engage the front end of the arm and hold it from moving on its pivot, said hook portion being constructed to automatically engage said mechanism when the handle is up and the latch is released, said forwardly extending portion and said latch being constructed for foot operation to cause their connection and disconnection, as desired.

6. A lifting truck, comprising, a carriage, a load supporting platform, links pivoted on each of the four corners of the carriage and to the platform, the two links at the front corners being provided with extensions above the platform, a cross rod connecting said extensions, a pivoted handle at the forward end of the truck, a hook arm pivoted directly to the handle and operable to connect and disconnect the handle with said cross rod, whereby when the handle is connected a downward sweep thereof will move the links on their pivots and the platform and carriage relatively one to the other for the links to elevate the platform.

7. The combination in a lifting truck of a carriage, comprising, a U-shaped bar, a rear axle connected with the cross-piece of said bar, an arched casting connecting the open ends of said bar, a steering wheel swiveled to said casting intermediate the sides thereof and wheels mounted on the rear axle outside of said bar, a U-shaped lifting platform, links pivoted to said axle outside the wheels and to the inner sides of said platform, other links connecting the forward ends of said bar and platform, a truck handle and means operated by the latter to turn said links on their pivots whereby the platform may be raised and lowered with respect to said bar.

8. A lifting truck, comprising, a carriage and a platform each formed of a single U-shaped frame piece, means fastened to the cross piece of the carriage on which rear wheels are mounted, an arched casting connecting the open end of the carriage frame having vertical slots between said casting and the side bars of the frame, links horizontally pivoted at their lower ends to the four corners of the carriage, those at the front being movable within and limited by said slots, said links forming a means to pivotally connect said carriage and platform, a truck handle operated means to swing said links on their pivots, whereby the platform is raised and lowered.

9. A lifting truck, comprising, a carriage having front and rear wheels, a platform including forwardly extending side bars, a rear axle, links provided with outwardly extending bosses and pivoted at the ends of

the rear axle outside of the rear wheels, links pivoted to the front corners of the carriage, all of said links serving to pivotally connect said platform and carriage, 5 stops on the latter to limit the pivotal movement of the links, whereby the latter may be operated to raise and lower the platform, said outwardly extending bosses being ar-

ranged to limit the downward movement of said side bars, a truck handle, and handle 10 operated means to move said links for the raising and lowering operations.
